UPHOLSTERY

Russell R. Thompson, Detroit, Mich., assignor to
The Murray Corporation of America, a corporation of Delaware

Application November 13, 1933, Serial No. 697,743

1 Claim. (Cl. 155—185)

The invention relates to vehicle bodies and it has particular relation to an improvement in the construction of the seat or seat back upholstering.

It is usual in upholstering seats and seat backs in vehicles to provide a plaiting having depressions and usually the depressed portions are connected to a backing by means including buttons on the exposed side of the upholstering. While this has been satisfactory practice, it is undesirable in that the buttons are visible and furthermore it requires penetrating the upholstery plaiting in inserting the buttons. Furthermore, it requires more time to upholster a seat or seat back in this manner.

An object of the invention is to provide an improved means for forming tufts or pinched-in portions in the plaiting which will eliminate the use of exposed buttons or the like, and furthermore eliminate the usual practice of passing fastening devices or retainers through the upholstery plaiting.

Other objects of the invention will become apparent from the following description, the drawing relating thereto, and from the claim hereininafter set forth.

For a better understanding of the invention, reference may be had to the drawing, wherein:

Figure 1 is a cross-sectional view of the back of a vehicle seat illustrating means constructed according to the invention for forming tufts in depressed portions of the plaiting.

Fig. 2 is a bottom plan view of the structure shown in Fig. 1.

Fig. 3 is a cross-sectional view taken substantially along line 3—3 of Fig. 1.

Fig. 4 is a detail view of the retaining clip employed.

Fig. 5 is an end view of the clip shown by Fig. 4.

Referring to Fig. 1, the plaiting cloth or other flexible finish material is indicated at 10 and a fabric backing at 11. The plaiting is tucked in along spaced lines indicated generally at 12 to form depressions, and between the depressions and between the backing 11 cotton or other suitable cushioning material may be provided. Rearward of the backing 11, cushioning padding 14 is provided and a layer of burlap or other retaining material 15 may be used to cover the padding. The upholstering may be fastened to the back of the seat or other rigid part thereof by tacking around the edge thereof, as will be readily understood.

According to the present invention the plaiting 10 and the backing 11 are sewn along the

bottoms of the depressions and this may be effected by forming nesting folds or laps 16 and transversely sewing therethrough as indicated at 17. This leaves a projecting and retaining fold along each depression at the back of the backing 11. For forming pinched-in portions or tufts in place in the depressions, as well as connecting the depressed portions to the burlap 15, metal clips 18 are employed and as best shown by Figs. 4 and 5, each of the clips comprises a reversely bent piece of metal having inwardly directed teeth 20 at its free edges. Initially these toothed portions are sufficiently apart that the clip may be applied over the folds and then by pressing opposed sides of the clips, the teeth 20 are pressed 15 or clamped into the cloth, thereby locking the clips thereto. Prior to applying each clip, a wire retainer 21 having a wide aperture 22 for receiving the clip is assembled with each clip, and then when the clip is applied, the wire retainer 20 is positively connected thereto. This retainer may be made by bending a piece of wire to the shape shown and overlapping the ends to provide a closed form.

For permitting application of the clips and subsequent access to the wire retainers, the padding 14 and burlap 15 may have openings 24. After application of the clips and wire retainers, heavier wires 25 at the back side of the burlap may be passed through the wire retainers 30 and to provide a firm assembly, the latter may have smaller and arcuately apertured ends 26 slightly larger than the wires. In inserting the wires, the padding 14 may be compressed, and after insertion of the wires, resilient return of the padding may cause the wires to form depressions 27. This arrangement will constantly maintain a tuft in the depressed portion of the plaiting at each clip so that at each clip, the plaiting will appear drawn or pinched in slightly 40 more than the ordinary depth of the depressions.

It is apparent that the front or exposed side of the plaiting will be free from buttons or other fasteners and the depressions will be clean and uninterrupted except for the pinched-in portions 45 or tufts at each clip. Moreover it will be apparent that the assembled plaiting and backing 11 with cotton or the like therebetween, may be assembled with the padding 14 and burlap 15, without any operation at the front side of the 50 plaiting. Application of the clips is relatively simple and insertion of the wires 25 may be easily accomplished. In general the invention provides a more efficient and economical structure and enhances the appearance of the upholstering. 55

Although only one form of the invention has been illustrated and described in detail, it will be apparent to those skilled in the art that various modifications may be made without departing 5 from the scope of the appended claim.

What is claimed is:

A cushion assembly comprising a supporting structure, an upholstery unit covering said structure and attached thereto, said upholstery unit 10 having inner and outer layers of padding, the

inner layer having sockets formed therein and the outer layer having ridges provided with portions projecting into said sockets, and metal clips substantially V-shaped in cross section and having angularly disposed inwardly projecting teeth positioned within said sockets and secured to the projecting portions of the ridges and connecting them to said supporting structure. 5
